MOSES BURLINGAME, OF GARRATTSVILLE, NEW YORK, ASSIGNOR TO HIMSELF AND JAMES E. PILKINGTON, OF WASHINGTON, DISTRICT OF COLUMBIA.

Letters Patent No. 97,749, dated December 7, 1869.

IMPROVEMENT IN MACHINES FOR MAKING CANDLE-MOULDS.

The Schedule referred to in these Letters Patent and making part of the same.

To all whom it may concern:

Be it known that I, MOSES BURLINGAME, of Garrettsville, in the county of Otsego, and State of New York, have invented a certain new and useful Machine for Making Candle-Moulds, Dipper-Handles, &c.; and I do hereby declare that the following is a full, clear, and exact description of the same, reference being had to the accompanying drawings, which make part of this specification, and in which—

Figure 1 represents a view, in perspective, of a machine embracing my invention, the blank from which the mould is formed being represented by dotted lines, in the position it occupies at the commencement of the operation;

Figure 2 represents a vertical longitudinal section, the body of the mould having been formed upon the mandrel;

Figure 3 represents a similar section, the tip of the mould having been formed by the operation of the point-swage or die;

Figure 4 represents a transverse section through the case and mandrel, the parts occupying the position shown in fig. 1;

Figure 5 represents a similar section, the parts occupying the position shown in fig. 2;

Figure 6 represents a view of the mandrel detached.

Figure 7 represents the blank from which the mould is formed;

Figure 8, the mould, formed without the tip; and

Figure 9, the mould completed, with its tip.

My invention consists in the construction and operation of a machine, by which candle-moulds are made, with their points or tips, from one and the same blank, at one and the same operation.

The machine by which this is effected, consists of a case or receiver, A, within which is formed a tapering opening, of a length and diameter corresponding to that of the mould to be formed, which also receives the mandrel B.

This case A is provided with a narrow slit or opening, *a*, extending from one end thereof to the other, which constitutes the feeding-channel for the blank to the mandrel B.

The case in which the mould is formed is mounted upon a bench, in any convenient manner, and supports at one end a swaging-die, C, for forming the tip of the mould, and at the other a crank, D, by which the mandrel B is operated, and devices for locking it within the case A, and bringing it to the proper position to receive the blank E through the feeding-opening *a*.

The mandrel B projects beyond each end of its receiving-case, and the difference between the diameter of said mandrel, and the opening within which it is fitted, must be equal to the thickness of the metal being formed.

The mandrel corresponds in form to the mould, and is provided with a groove, *b*, of a length equal to the blank, from the base of the tip to the mouth of the mould, for the purpose of receiving the edge of the blank E, so that it will bite upon and hold it tightly, when the act of turning the mandrel will draw the blank through the feeding-opening.

In order to prevent any longitudinal motion of the mandrel B, while forming the mould, it is provided with a groove, *c*, just outside of the end of the receiving-case A, into which an arm, F, fits, at right angles to the mandrel, so as to form a lock.

This arm F is pivoted to the case A, so that it may be turned upward, to unlock the mandrel, and allow it to be withdrawn for the removal of the finished mould.

In inserting the blank E into the feeding-opening *a* of the case, it would be difficult to present the groove *b* of the cylinder beneath the feeding-groove *a*, so that the blank could be inserted therein with exactness.

In order, therefore, that the biting-groove *b*, of the cylinder, may be presented at once to receive the blank, I hinge a dog, G, to the end of the case, so that its inner toothed end *e* shall always rest upon the end of the mandrel B, outside of the locking-arm F, in such manner that the tooth *e* of the dog will fit into a groove, *d*, in the end of the mandrel, so as to arrest it at a point where the groove *b*, in the mandrel, and the feeding-opening *a*, in the case, will be coincident. For this purpose the toothed end *e*, of the dog G, must be sufficiently heavy to keep it down upon the mandrel, while one side of the notch or groove *d*, within which the tooth *e* interlocks, must be bevelled, to allow the toothed end of the dog to pass over the mandrel without interrupting its motion, while the other side of the notch forms a shoulder, and, by turning the mandrel backward, interlocks with the tooth of the dog, and thus brings the mandrel always with facility and correctness in the proper position to receive the blank.

The end of the locking-arm F extends beyond the side of the receiving-case A, and is maintained in its locked position with the mandrel by a self-locking latch, H, which allows said pivoted arm to be readily thrown back from the mandrel.

When the pivoted arm F is unlocked from the mandrel B, it is necessary, also, to remove the dog G out of the way, to allow the mandrel to be withdrawn; and, for this purpose, the said pivoted arm is caused to strike upon the outer end *s* of the pivoted dog G, when thrown back, and thus raise the toothed end *e* of the latter entirely out of the way of the withdrawal of the mandrel, and, the toothed end of the dog being heaviest, its release from the pivoted arm will, of course, bring it down again upon the end of the mandrel.

In the manufacture of candle-moulds, as heretofore practised, the tip has been made of a separate piece of metal, formed into a cone, and then soldered to the mould, after the formation of the latter, which not only increased the expense of the mould, but consumed much time in the manufacture of the article.

In order, therefore, to form the tip at one and the same operation with the formation of the mould, and from one and the same piece of metal, I cut or stamp the tapering end of the blank *E* with three or more teeth *f*, each having the form of a cone, the bases of which are on a line with the base of the tip of the mould, so that when the body of the mould is formed by the mandrel *B*, the tip of the mould will consist of conical-shaped projections *f*, with intervening V-shaped spaces, which project from the case *A*, and surround the conical point *g* of the mandrel *B*.

To bring these teeth together over the tapering point of the mandrel, I arrange a swaging-die, *C*, having its centre coincident with the axis of the mandrel, fitted to slide upon ways *h*, projecting from the rear end of the case *A*, and provided with a socket, *I*, corresponding in form to the conical end *g* of the mandrel, but slightly larger in size, to compensate for the thickness of the metal, so that when the swage *C* is brought up to form the tip, the projecting teeth *f* of the mould pass within the opening *I* of the die, and of course the forcing of the latter directly over the projecting end *g* of the mandrel will close the conical teeth together, so that their edges join each other, and the intervening spaces closed up, thus forming the tip of the mould.

The swaging-die *C* is brought into action, to form the conical tip of the mould, by means of a cam-lever, *J*, pivoted to the rear end of the frame, so as to act against an anti-friction roller, *r*, on the rear side of the swaging-die *C*, and force it up close against the rear end of the receiving and forming-case *A*, so as to entirely enclose the conical end *g* of the mandrel, in which position it is locked by means of a latch-lever, *K*, pivoted to the side of the frame, so that its weighted end will always be in position to pass over the handle of the cam-lever *J*, and latch itself therewith.

The swaging-die *C* is forced back from the mandrel *B*, after the completion of the mould, by means of a spring, *i*, acting upon a central longitudinal rod, *j*, attached to the under side of the swaging-die *C*, so that it is only necessary to lift the latch *K* from the handle of the cam-lever *J*, when both the lever and the swaging-die are forced back, as before stated, in a position to be in readiness to form the tip of the next mould.

The mould thus formed, it will be seen, is still locked in the groove *b* of the mandrel by its bent lip *n*.

To release it from the mandrel *B*, and to straighten it, so that it may be withdrawn from the mandrel a perfect mould, with the edges just overlapping each other, I secure in openings formed in the side of the forming-case, so as to communicate with the interior opening therein, two or more rods, *m*, placed so as to strike the mould obliquely to a horizontal line, as shown in fig. 5, having their inner ends rasped, and their outer ends united by a connecting-plate, *L*, secured by a screw to the case, the shank of said screw allowing the plate *L* to move, with its arms *m*, toward and from the mandrel *B*, while a spring, *O*, arranged between the case and the plate *L*, constantly tends to force the latter outward, so that when the bent lip *n* of the mould is desired to be released from its locking-groove *b*, it is only necessary to press the plate *L* inward, which carries the rasped ends of the oblique arms *m* directly against the side of the mould, so as to press and bite thereon with

sufficient force to prevent the mould from turning, while, with a quick turn of the mandrel *B*, the said bent edge is released from its groove *b*, and made to conform to the curve of the mould, and thus the mould is completed.

Instead of the means just described of straightening the bent lip *n* of the mould, so that it will conform to the curve of the mould, the mandrel, with the mould thereon, may be drawn half way out of the cylinder, so that the bent lip *n* may be liberated from its holding-groove on said mandrel, the mould turned partly around, and pressed back to its original place in the forming-cavity, with its edges slightly overlapped. One revolution given to the mandrel, and the required cylindrical form is imparted to the mould.

The blank *E*, from which the mould is made, is first cut or stamped from a sheet of metal, of the required size and shape, as represented in fig. 7.

It is then placed within the opening *a* of the receiving-case *A*, and fitted securely in the groove *b* of the mandrel *B*, so as to stand in a vertical position, as shown in fig. 1, one side of the opening *a* in the case being bevelled, to facilitate its entrance therein.

The attendant then grasps the crank *D* of the mandrel, and turns it, which bends the lip *n* of the blank into the groove *b*, so as to lock it with the cylinder; then continuing to turn the mandrel one revolution, it will draw the blank through the opening and around said mandrel.

The swaging-die *C* is then brought into action by means of the cam-lever *J*, to form the conical tip of the mould, closing up the conical teeth *f* of the blank, and another revolution is given to the mandrel, to render the joints of the tip even.

The rasped ends of the oblique rods *m* are then pressed sharply against the mould on the mandrel, with sufficient force to prevent it from turning while the mandrel is turned quickly by its crank *D*, so as to liberate the locking-lip *n* of the mould from its groove *b*, thus bringing it into the proper form.

The swaging-cam *J* is released, the locking-arm *F* is thrown back, the mandrel *B* withdrawn from the forming-case *A*, the mould removed, the mandrel replaced and locked within the forming-case, and the machine is in readiness for the formation of another mould.

In this manner moulds may be made with great facility, requiring only to have the joints of the body and the tip soldered in the usual manner.

Dipper-handles, and other similar articles, may also be made with great facility, and at a great saving of expense, by this machine.

Having thus described my invention,

I claim—

1. Candle-moulds, with their tips, formed from the same blank, at one operation, by machinery constructed substantially as described.

2. The combination of a mandrel, *B*, provided with a longitudinal groove, *b*, the enclosing forming-case *A*, having a feeding-opening, *a*, and swaging-die *C*, having a socket, *I*, all arranged and operating substantially as described.

3. The combination of the pivoted dog *G* with a mandrel, constructed with a notch or groove, *b*, for arresting the motion of the mandrel in the proper position to be locked with the blank, substantially as described.

4. The sliding biting arms *m*, for holding the mould within the case, for the purpose of allowing the mandrel to be turned independently of the mould, to unlock the latter therefrom, substantially as described.

5. The combination of the pivoted arm *F*, for locking the mandrel within the case *A*, with the toothed

dog G and swaging-die C, all arranged and operating substantially as described.

6. The combination, in a machine for forming candle-moulds from a single blank, at one and the same operation, of a receiving-case, A, a forming-mandrel, B, a swaging-tip die, C, sliding biting arms *m*, pivoted locking-arm F, and arresting-dog G, all constructed, arranged, and operating substantially as described.

7. A candle-mould, with its tip made from a single

blank, provided with V-shaped projections at one end, as a new article of manufacture, substantially as described.

In testimony whereof, I have hereunto signed my name.

MOSES BURLINGAME.
